US00D645259S

(12) **United States Design Patent**
Steeman et al.

(10) **Patent No.:** **US D645,259 S**
(45) **Date of Patent:** ** *Sep. 20, 2011

(54) **FILM SHEET FOR USE IN ANTIBALLISTIC ARTICLES**

(75) Inventors: **Reinard Steeman**, Elsloo (NL); **Marcel Jongedijk**, Sittard (NL)

(73) Assignee: **DSM IP Assets B.V.**, Heerlen (NL)

(**) Term: **14 Years**

(21) Appl. No.: **29/338,875**

(22) Filed: **Jun. 19, 2009**

(51) LOC (9) Cl. **05-06**

(52) U.S. Cl. **D5/58**

(58) **Field of Classification Search** ..... D5/1, 2, D5/3, 5, 7, 8, 11, 13, 14, 15, 16, 19, 20, 23, D5/24, 25, 26, 27, 28, 30, 32, 35, 36, 37, D5/39, 43, 45, 46, 47, 49, 50, 52, 53, 54-58, D5/59-61, 62-66, 99; D2/749, 994; D6/582, D6/583, 595, 596, 597, 598, 603, 604, 605, D6/606, 608, 613, 616, 617, 619, 622; 428/17, 428/18, 151, 154, 156, 171, 187, 198, 199, 428/540, 542.2, 542.6, 904.4, 919; D24/124, D24/125, 126; D25/142, 152; 5/413 A, 709 M; 162/109, 134, 140, 231; D32/57; 52/506.05; 362/148; D21/348, 349; 139/383 R, 420 C, 139/420 B, 424, 420 R, 418, 413, 420 A, 139/419; 273/260, 161

(57) **CLAIM**

The ornamental design for a "film sheet for use in antiballistic articles," as shown and described.

DESCRIPTION

FIGS. 1 and 2 are top and bottom plan views, respectively, of an embodiment of a film sheet for use in antiballistic articles which embodies our new and original design therefore, the side views thereof being unornamented;

FIGS. 3 and 4 are top and bottom perspective views, respectively, of the embodiment thereof depicted in FIGS. 1 and 2; FIGS. 5 and 6 are top and bottom plan views, respectively, of another embodiment thereof, the side views thereof being unornamented; and,

FIGS. 7 and 8 are top and bottom perspective views, respectively, of the embodiment thereof depicted in FIGS. 5 and 6. The broken lines in the drawing represent the bounds of the claimed design and form no part of the claimed design.

1 Claim, 8 Drawing Sheets
